UNITED STATES PATENT OFFICE.

JOHN H. BANKA, OF BATTLE CREEK, MICHIGAN.

RIM TOOL.

Application filed April 13, 1927. Serial No. 183,393.

This invention is a novel improvement in so-called rim breakers, or tools for contracting and expanding split demountable rims such as are commonly employed in connection with pneumatic tires for wheels of automobiles and the like.

The object of the invention is to provide a novel tool for this purpose which has few parts, is extremely simple and inexpensive to make, requires very little space in the tool kit, and operates perfectly on split rims of any size; and the tool is so constructed that it not only can be used to engage the rim, force its ends out of alinement and draw it to the smaller diameter, but can also be used to force the rim back to its alined position even against the resistance of the tire casing.

I will explain the invention with reference to the accompanying drawings which illustrate a practical tool embodying the same, and set forth in the claims the novel features and construction of parts for which protection is desired.

In said drawings:

Figure 1 shows the tool attached to a split rim ready for breaking the same.

Fig. 2 is a similar view showing the parts adjusted to force the end of the rim out of circular alinement;

Fig. 3 shows additional parts of the tool after it has broken the rim and contracted the circumference thereof and its removal of the tire;

Fig. 4 is a top plan view of the complete tool as appears in Fig. 1;

Fig. 5 is a transverse section on line 5—5, Fig. 4.

The device comprises clamp members engaged with the rim at opposite sides of the split therein, eye-bolts pivoted to the clamp members; a turn-buckle connecting the two bolts; a presser bar pivoted on one of the bolts and having one end adapted to engage the rim at one side of the split therein and provided with an adjustable bolt in its opposite end adapted to engage the rim at the opposite side of the split, the several parts being preferably constructed as illustrated in the drawing, as follows:

Each clamp member comprises a bolt 1 which passes through eyes 2^a of hooks 2 respectively adapted to engage opposite sides of the rim and be securely confined thereto by tightening a thumb nut 1^a on the bolt 1.

Pivoted on each bolt 1 is an eye-bolt 3 having an eye 3^a engaged with the bolt and

its threaded shank is engaged with a turn buckle 4. By turning this buckle 4 the clamp members can be drawn toward or forced away from each other.

A presser bar 5 is pivoted upon one of the bolts 1 beside the eye bolt 3 thereon and projects at opposite sides of said bolt 1. One end of the presser bar 5 is preferably bent outwardly as at 5^a so as to engage the rim at one side of the split, as shown, and on the other end of the presser bar is mounted on adjustable bolt 6, which may be a thumb bolt, and which is adapted to be adjusted into engagement with the rim at the side of the split opposite end 5^a so as to forcibly rock the presser bar on the bolt on which it is mounted.

In applying the device the clamp member carrying the presser bar 5 is attached to the rim closely adjacent the split therein as indicated in Fig. 1, the turn buckle having been first expanded. The other clamp member is then engaged with the rim at the opposite side of the split and approximately as far therefrom as turn buckle will permit. The bolt 6 on the presser bar is then turned inwardly to forcibly engage the rim and rock the presser bar on its pivot and cause the rim to break, as indicated in Fig. 2, the presser bar forcing the ends thereof out of circular alinement. Then the turn buckle 4 is turned so as to draw the clamp members toward each other until the rim is contracted, as indicated in Fig. 3.

In its contracted position the tool holds the rim in position to receive the tire when it is ready to be again mounted upon the rim. The tool is also adapted to force the rim back to its normal alined position after the tire has been replaced by reversing the operations above described. The turn buckle being turned back to restore the parts from the position shown in Fig. 3 to the position shown in Fig. 2, and then the thumb screw turned backward to allow the ends of the rim to again come into circular alinement as in Fig. 1.

While I at present prefer to use a thumb screw or bolt as 6, it is obvious that other equivalent means might be used for rocking the presser bar for the purpose specified.

The tool can be folded into a small compact form, easily carried in any tool-kit, or for convenience placed in a small sack by itself. It can be very quickly attached to or removed from the rim; and used to break

the rim and contact it, and then used to expand it back into position by reversing the operations above described. The tool is suitable in every way for the purpose of 5 quickly and easily changing a tire on a split rim without distorting the rim, or requiring the use of any other tool.

I claim:

1. A rim breaker, comprising a pair of 10 clamps adapted to engage the rim at opposite sides of the split therein, each clamp comprising members to engage opposite sides of the rim and a tie-bolt for securing said members to the rim; adjustable means connecting the clamps whereby they may be moved to or from each other, and a presser bar pivotally mounted upon one of the tie-bolts and extending toward the other clamp 15 sufficiently to span the split and engage the far rim end and operable independently of the said connecting means to break the rim.
2. A rim breaker comprising a pair of 20 clamps adapted to engage the rim at opposite sides of the split therein, each clamp comprising hooks to engage opposite sides of the rim and a tie-bolt for securing said hooks to the rim; adjustable means connecting the clamps whereby they may be moved to or from each other; a presser bar pivotally 25 mounted upon one of the tie bolts and having one end extended towards the other clamp sufficiently to engage the rim at one side of the split and means connected with the other

end of the presser bar to engage the rim at the other side of the split to operate the 35 presser bar.

3. A rim breaker, comprising a pair of 40 clamp members adapted to engage the rim at opposite sides of the split therein, each clamp member comprising hooks to engage 45 opposite sides of the rim and a tie-bolt for securing said hooks to the rim; a turn-buckle connecting the clamp members; and a presser bar pivotally mounted upon one of the tie-bolts and extending towards the other clamp sufficiently to span the split and engage the far rim end and operable independently of the contracting operation of the turn-buckle.

4. A rim breaker comprising a pair of 50 clamp members adapted to engage the rim at opposite sides of the split therein, each clamp member comprising hooks to engage opposite sides of the rim and a tie-bolt for securing 55 said hooks to the rim; a turn-buckle connecting the clamp members; a presser bar pivotally mounted upon one of the tie-bolts and having one end extended towards the other clamp sufficiently to engage the rim at one side of the split; and means connected with the other end of the presser bar to engage the rim at the other side of the split to operate 60 the presser bar.

In testimony that I claim the foregoing as my own, I affix my signature.

JOHN H. BANKA.
